COMBINED CRIB AND DRAWER CHEST

Max Stettner, Los Angeles, Calif.

Application May 6, 1948, Serial No. 146,196

Term of patent 14 years

(Cl. D5—5)

To all whom it may concern:

Be it known that I, Max Stettner, a citizen of the United States, residing at Los Angeles, in the county of Los Angeles and State of California, have invented a new, original, and ornamental Design for a Combined Crib and Drawer Chest, of which the following is a specification, reference being had to the accompanying drawing, forming part thereof.

Figure 1 is a perspective view of a combined crib and drawer chest embodying my new design, the drawers of the drawer chest being illustrated in closed position; and

Fig. 2 is a perspective view of the same taken from the opposite corner, the drawers being illustrated in partially open position.

I claim:

The ornamental design for a combined crib and drawer chest, as shown.

MAX STETTNER.
